UNITED STATES PATENT OFFICE.

PAUL JOHN TIMBERLAKE, OF JACKSON, MICHIGAN.

VEHICLE-DASHBOARD FRAME.

SPECIFICATION forming part of Letters Patent No. 692,945, dated February 11, 1902.

Application filed November 17, 1900. Renewed June 18, 1901. Serial No. 65,084. (No model.)

To all whom it may concern:

Be it known that I, PAUL JOHN TIMBERLAKE, a citizen of the United States, residing at Jackson, in the county of Jackson and State 5 of Michigan, have invented certain new and useful Improvements in Vehicle-Dashboard Frames, of which the following is a specification, reference being had therein to the accompanying drawings.

10 The object of this invention is to provide a device to be used in connection with the dashboards of buggies and similar vehicles by which several desirable ends can be attained. These dashes, as is well known, are in many 15 cases quite light in their structure and more or less liable to straining and twisting and being otherwise marred or injured. This is particularly true where whip-sockets, rein-holders, and other attachments are secured 20 to them.

The devices to which this invention relates are intended to overcome these disadvantages, to strengthen and brace the dash as a whole, to provide a rest for the reins, and to, when 25 desired, securely fasten the latter in place, and to increase the ornamental and tasty appearance of this part of the vehicle.

Figure 1 is an elevation of a device embodying my improvements, it being here illustrated as seen when looking forward from the buggy. Fig. 2 is a top edge view of the same. Fig. 3 is a rear view of a modification. Fig. 4 is a similar view of another modified form. Fig. 5 is a vertical section on the line $x-x$, Fig. 1. Fig. 6 is a vertical section on the line $y-y$ of either Fig. 3 or Fig. 4. Fig. 7 is a vertical section on the line $z-z$, Figs. 1, 3, and 4. Figs. 8, 9, and 10 are rear views of further modifications. Fig. 11 is a top edge 35 view of the structure shown in Fig. 3. Fig. 12 is a top edge view of the structure shown in Fig. 9. Fig. 13 is a top edge view of the structure shown in Fig. 10. Figs. 14 to 18 illustrate the several forms of the device 40 shown, respectively, in Figs. 1, 4, 8, 9, and 10, they being here illustrated detached and in the condition in which they are manufactured as separate articles prior to attachment to the dashes.

50 In the drawings the dash of a buggy or similar vehicle, or a sufficient portion thereof

to assist in understanding the invention, is indicated by A. This is formed of the frame-bars $a-a$, at the ends with the top bar a' and the bottom bar a^2 , and the leather a^3 , which 55 is secured to the marginal frame-bars by stitching. As concerns this part of the article, it will be understood that it can be made in any well-known or in any suitable way. As above remarked, these dashes, particularly in the lighter forms of vehicles, are themselves light and simple in appearance and require supplemental parts for strengthening, bracing, and permitting the securing of other attachments. 60

Referring at first to the parts in Figs. 1, 2, and 5, B indicates a device of one of the forms embodying my improvements. It is, as an entirety, capable of being attached to and detached from the dash structure. It is composed of the standards $b-b$, each having a downwardly-extending leg or plate b' and the rail or bar b^2 . The standards $b-b$ are formed with eyes b^3 , through which the rail b^2 is passed and in which the latter is fastened 75 by brazing, soldering, or equivalent process. The rail extends from side to side of the dash, and the standards $b-b$ are clamped against the latter, they and the rails thus serving as a bracing and strengthening device. In the 80 construction now being described the rail is at the sides of the dash bent upward, outward, and downward to form relatively large loops b^4 , that part of the bar at b^5 serving as a guard or retaining device for the reins to 85 prevent their lateral displacement either when held loosely in the hands of the driver or when they are secured in the holder.

To increase the strength and stability of the rail, its ends are carried inward from the 90 loops b^4 and pass through eyes or sockets b^6 in the standards b and extended thence still farther inward toward the center, their inner ends being provided with balls or knobs b^7 , which prevent said ends from engaging with 95 or tearing clothing or other bodies which may come into contact with them. Preferably the end parts of the rail at b^8 are turned somewhat backward to stiffen the rail-frame, to enhance the tasty appearance, and to assist 100 in guiding the reins into the holder when the frame is to be used for that purpose. These

purposes can be accomplished by bending the central part of the upper bar B slightly forward.

When the rail-frame is constructed in the way above described, it will be seen that I provide means for firmly gripping and holding the reins independently of the dash. The parts at b^8 b^9 of the rail-bar are so arranged relatively to the upper main part b^2 that one or both of the reins can by an easy lateral movement be slipped between these two parts of the rail and be pinched or clamped as tightly as desired. By examining Figs. 5 and 6 it will be seen that these parts of the rail-frame should be suitably near to the top of the dash so that the free end or ends of the reins can fall down against it and assist in preventing the forward slipping thereof.

In Fig. 3 a modified form of rail-frame is shown, the parts of which, however, as concerns the ends attained by them, are substantially similar to those above described, and shown in Figs. 1 and 2. In this case the loops at the outer ends are dispensed with and guards are provided by extending the ends of the rails C upward, as shown at c^5 , and their extremities are provided with knob guards or balls c^{11} . The standards at $c\ c$ for securing the rail to the dash are similar to those at b , except that they each have but a single socket or eye. A third standard c^{10} is here used, which not only furnishes an additional strengthening and supporting brace for the main rail and for the dash, but also provides a carrier for rigidly holding the supplemental rail or bar C', the latter being fastened in the socket c^6 . This bar at its extremities is bent backward somewhat, as at c^8 , and furnished with knobs or balls c^7 . Thus it will be seen that here also I provide the guard-rail for the dash and also a rein holding and securing means which is virtually a part of the rail-frame and is attachable and detachable therewith in relation to the dash.

In Figs. 4, 8, 9, and 10 there are shown other modifications of the rail-frame, by which all of the above-described ends can be attained, as well as others in addition thereto. In some cases it is desirable to still further strengthen and stiffen the dashboards and to provide hand-bars by which the rider is assisted in getting into and out from the vehicle. In such instances I employ an inner rail or bar, as shown in the figures last designated. Turning to Fig. 4, this supplemental bar is indicated by D'. In this case it extends from side to side of the dash and terminates near its side vertical line, being provided with knob-guards d^{11} . It is supported in and rigidly fastened in sockets d^{12} , formed in the standards $d\ d$, by which the rail-frame is secured to the dash. The upper bar or rail D is substantially similar to that at B in the construction shown in Fig. 1—that is to say, it has a central part d^2 approximately straight and secured in the eyes d^3 . At the outer parts it is bent to form loops d^4 and has its downward

and inward turned ends secured in loops d^4 in the standards. The end parts project toward the center from the standards, they being curved backward at d^8 and provided with balls d^7 . Here I provide not only an increased strength and stiffness for the rail-frame as a whole, but furnish means for relieving the dash entirely of service in holding the reins. The ends of the latter are pinched or gripped between the projecting end parts d^8 d^9 of the projecting ends of the bar and the top rail part d^2 and the lower rail D'. The said end parts can be somewhat elastic or resilient; but such quality is not necessary to attain the purposes aimed at.

In Figs. 8, 9, and 10 the supplemental rail is so formed and attached as to still further enhance the stiffening and strengthening of the dash and of the rail-frame. In Fig. 8 it is indicated as a whole by E'. It is formed with the top transverse part e^{13} and the vertical parts e^{14} , terminating at the bottom in attachment foot-pieces e^{15} , by which it is secured to the lower part of the dash. The vertical side parts e^{14} are substantially parallel to, but somewhat outside of, the end edges of the dash, so that they also serve as hand-loops to assist in entering or descending from the vehicle. The upper rail (indicated as a whole by E) and the standards e are substantially similar to the corresponding parts in Figs. 1 and 4, above described, and will be readily understood without further description.

In Fig. 9 a construction is shown in which the principal rail of the frame is at the top line of the latter, as shown at F, the cross-bar being indicated by f and the downward-extending parts at f' , these being secured in the manner above described to the lower part of the dash and having a free space between them and the side edges of the latter. The stiffening-bar F' is between the upper edge of the dash and the bar f. The standards f^2 f^2 carry the transverse bars and detachably connect them to the dash. These two transverse or cross bars in this construction are supplementally braced together at the center by a bracket f^3 . This bracket carries a short third bar, whose oppositely-projecting ends are curved somewhat backward at f^4 and terminate in guards f^5 .

With respect to that feature of the invention which relates to so constructing the rail-frame that it can be used to tightly pinch or grasp the reins, it will be noticed that in the devices above described the free ends, which are turned somewhat backward, are in each case located relatively near the center plane of the vehicle; but in some cases it is better to have the rein support and gripper at considerable distance from the center, and when my plan is followed for constructing the parts of the rails this can be readily accomplished. Thus in Figs. 10 and 13 a construction is shown in which the principal rail of the frame is shown at G extending from side

to side of the dash and turned inward above the outer edges of the dash, as at g , and secured to the dash by the standards g' and then curved outward again, as at g^2 , and with the 5 terminals curved backward, as at g^3 , and provided with the guard-knobs g^4 . The backwardly-curved parts g^3 serve to support the reins, as in the other structures shown. In this structure the stiffening-bar G' is between the 10 upper edge of the dash and the bar G and is supported by the same standards g' which support the parts g and is turned downward on each side, as at g^5 , and attached to the dash by foot-pieces g^6 .

15 The central portion of the top rail G is depressed, as shown, and connected centrally to the stiffening-rail G' by a clip g^7 to add stiffness to the structure. When the reins are held in the hands and are resting on the 20 top cross-bar G , the upwardly-turned parts at g^8 serve as a guard against lateral displacement; but when they are fastened in the holder they are held on lines quite remote from the back of the horse and are not liable 25 to accidental loosening.

I am aware of the fact that numerous devices have been suggested, on the one hand, for stiffening or strengthening vehicle-dashes, and, on the other hand, for attaching devices 30 directly to the dashes for holding whips, reins, &c.; but I believe myself to be the first to have provided an article which as an entirety can be considered as entirely independent of the dash and whose parts are so constructed and related that they furnish the 35 desired bracing and stiffening of the dash from one side to the other; secondly, greatly enhance the ornamental appearance of the article, and, thirdly, furnish means for readily and quickly gripping or unfastening the 40 reins. Such an article as I have described and capable of meeting all of these ends can be manufactured in its complete form and furnished to the carriage-builders ready for 45 application to the vehicle.

It will be readily seen that numerous other modifications can be produced without materially departing from the essential features of the invention which I present, those shown 50 herein being selected as types for the purpose of illustration.

What I claim is—

1. A rail-frame for a vehicle-dash having 55 a bracing and ornamenting rail extending across the top of the dash, means for attaching it to the dash, and a rein-holder secured to said frame independently of the dash, substantially as set forth.

2. A rail-frame for a vehicle-dash having 60 a bracing-rail, adapted to be attached to the dash at a distance therefrom and extending across its top, means for attaching the rail to the dash, and a bar adjacent to the said rail, and attachable and detachable therewith, and 65 adapted to clamp a rein against the said rail, substantially as set forth.

3. A strengthening and ornamenting rail-

frame for a vehicle-dash having attaching-standards, a bar extending across the dash rigidly attached to said standards, and two 70 oppositely-extending bars with free ends and rigidly connected with the aforesaid bars and adapted to clamp the ends of reins against it, substantially as set forth.

4. As an article of manufacture, a vehicle-dash rail-frame having two parallel bars and two bars intermediate thereof bent as described to permit the fastening of straps between the intermediate bars and those at the sides thereof, and means for fastening said 80 frame to a vehicle-dash, substantially as set forth.

5. As an article of manufacture, a dash rail-frame having two adjacent bars and one or more intermediate bars with one or more free 85 ends, the end parts and the adjacent bars lying in different planes whereby means are provided for the grasping of straps between the intermediate bar and the adjacent bars, and means for detachably fastening said 90 frame to a dash, substantially as set forth.

6. As an article of manufacture, a vehicle-dash frame having two adjacent bars adapted to extend across the top of a vehicle-dash, and leg-bars e^{14} adapted to be placed by the 95 sides of the dash, an arm or arms with free ends between the said bars and lying in planes other than those of the said bars, and means for securing the said parts of the frame together, and to a vehicle-dash, substantially 100 as set forth.

7. As an article of manufacture, a vehicle-dash frame having a bar as at E adapted to extend across the top of a vehicle-dash, said bar being bent backward upon itself at its 105 ends to form arms having the end parts disposed substantially as set forth relative to the main part of the bar to permit the grasping of a strap between the said bar and the said end parts, as described.

8. As an article of manufacture a vehicle-dash rail-frame having a bar adapted to extend across the top of a dash, said bar being bent back upon itself at its ends and having the end parts in planes other than the plane 115 of the main central part of the bar, and protecting enlargements on the free ends, substantially as set forth.

9. As an article of manufacture, a vehicle-dash rail-frame having the brackets for securing it to the dash, a bar adapted to extend across the dash and seated in eyes in the said bracket and a supplemental bar or bars, having arms with two free ends, also held in apertures in the said brackets, said free ends 120 being arranged substantially as set forth to permit the grasping of straps by the rail-frame, as described.

10. As an article of manufacture, a vehicle-dash rail-frame having two brackets, as at b , 130 b each with two apertures, a rail or bar adapted to extend across the top of the dash, the central part of said bar being secured in one of the apertures in each bracket, and said bar

having its ends bent back toward said central part, and secured in the other eyes of the brackets and arranged in planes other than those of the central part of the bar, substantially as set forth.

11. A combined rail-frame and rein-holder for a vehicle-dash, it having two horizontally-arranged bars above the dash, one of which has its ends projecting freely, and both bars being more or less in substantially the same vertical planes except that the said free ends where one of the said bars is bent so as to lie in vertical planes different from those of the adjacent portion of the other bar.
- 15 12. A combined top rail-frame, rein-holder and hand-rail for a vehicle-dash, it comprising two parallel bars rigidly connected together and to the dash, one of said bars having freely-projecting ends lying in vertical planes other than those of the adjacent parts

of the neighboring bar, the last said bar being extended downward and secured to the sides of the dash.

13. In a dash rail-frame the combination of two vertically-arranged standards adapted to be secured to the rim of the dash, a bar connecting and rigidly secured to the two standards, a supplemental bar adjacent to the aforesaid bar, the said two bars being detachable together from the dash and being shaped relatively to each other substantially as set forth to provide a rein-holder wherein the reins can be slipped and clamped between the said bars.

In testimony whereof I affix my signature in presence of two witnesses.

PAUL JOHN TIMBERLAKE.
